(57) **CLAIM**

The ornamental design for a shredder, as shown and described.

DESCRIPTION

FIG. 1 is a perspective view of a shredder showing a first embodiment of the new design;

FIG. 2 is a top plan view of the shredder of FIG. 1;

FIG. 3 is a front elevation view of the shredder of FIG. 1;

FIG. 4 is a right side elevation view of the shredder of FIG. 1;

FIG. 5 is a left side elevation view of the shredder of FIG. 1;

FIG. 6 is a rear elevation view of the shredder of FIG. 1;

FIG. 7 is a bottom plan view of the shredder of FIG. 1;

FIG. 8 is a perspective view of a shredder showing a second embodiment of the new design;

FIG. 9 is a top plan view of the shredder of FIG. 8;

FIG. 10 is a front elevation view of the shredder of FIG. 8;

FIG. 11 is a right side elevation view of the shredder of FIG. 8;

FIG. 12 is a left side elevation view of the shredder of FIG. 8;

FIG. 13 is a rear elevation of the shredder of FIG. 8; and,

FIG. 14 is a bottom plan view of the shredder of FIG. 8.

The broken lines shown in FIGS. 8-14 that are immediately adjacent to the shaded areas and define unshaded regions, represent the bounds of the embodiment in which they are shown, while all other broken lines are directed to environment and are for illustrative purposes only; the broken lines form no part of the embodiment in which they are shown.
